UNITED STATES PATENT OFFICE.

JOHN B. WEST, OF SYRACUSE, NEW YORK.

AUTOMATIC AUXILIARY AIR VALVE FOR INTERNAL-COMBUSTION ENGINES.

Application filed June 10, 1918. Serial No. 239,153.

To all whom it may concern:

Be it known that I, JOHN B. WEST, a citizen of the United States, and a resident of Syracuse, in the county of Onondaga and State of New York, have invented new and useful Automatic Auxiliary Air Valves for Internal-Combustion Engines, of which the following is a specification.

This invention has for its object an electrically operated air valve for internal combustion engines of the type of valve described in my pending application, Sr. No. 193,393, filed September 26, 1917, which air valve is simpler in construction, more economical in manufacture than the valve of my pending application, and which also can be made by automatic machinery. Other objects appear throughout the specification. The invention consists in the combinations and constructions hereinafter set forth and claimed.

In describing this invention, reference is had to the accompanying drawings in which like characters designate corresponding parts in all the views.

Figures 1 and 2 are respectively an elevation and a vertical sectional view of my air valve the bracket being omitted in Fig. 2.

Figure 3 is an end view of the valve piece. Figure 4 is a face view of the supporting bracket and contiguous part.

Figure 5 is a diagrammatic view showing one way of making the electrical connection with the generator circuit.

Figure 6 is a similar view showing another way of making the electrical connections for Ford cars.

Figure 7 is a diagrammatic view showing one way of applying my invention to an engine.

Fig. 7^a is a fragmentary view similar to Fig. 7 showing another way of applying my invention to the engine.

Figure 8 is a fragmentary diagrammatic view illustrating my auxiliary air device connected in the pipe of the vacuum feed system.

This auxiliary valve comprises generally, a hollow body formed with inlet and outlet ports in one portion thereof, electromagnet windings around another portion of the body, a valve piece within the body to control said ports, an armature or core within the body and connected to the valve and preferably forming the extension thereof, and means for limiting the movement of the

core to control the extent of the opening movement of the valve and for holding the valve open.

The body is here shown as in the form of a tube 1 having inlet and outlet ports 2, 3 opening through the periphery of the lower portion thereof.

4 are the electromagnet windings around the intermediate portion of the body 1, these windings being usually made upon a spool which is placed upon the body between two heads 5, 6.

7 is a valve casing cylindrical in general outline and having an intermediate transverse partition 8 formed with a threaded opening which threads upon the lower threaded portion of the body 1 until the partition is located between the ports 2, 3, which are spaced apart in a direction lengthwise of the body 1, this partition separating the casing into inlet and outlet chambers 9, 10 below and above the partition 8. The upper end of the casing is closed by a head or nut 11 which is placed on the tubular body 1 before the casing 7 is placed on the body, and the lower end of the casing is closed by a similar head or nut 12 threading on the body against the lower end of the casing. The casing is also provided with suitable inlet and outlet ports 13, 14 to which the pipes may be connected in any suitable manner as by a coupling 15, the inlet port being connected to a pipe 15^a for conducting hot air to the inlet chamber 2 and the outlet port 14 being connected by a pipe as 16 to the intake manifold.

17 designates the core located in the tubular body 1 and extending into the portion thereof encircled by the magnet windings 4. This core is formed with an integral extension extending into the casing 7 and constituting the valve 18. The valve is formed with a reduced portion 19 and with faces 20 and 21 at opposite ends of the reduced portion which faces serve to balance the valve so that it is not affected by the suction in the engine cylinder. In other words, the valve is a balanced valve.

To further facilitate balancing of the valve so that the only factor to be taken into consideration is the current passing through the electromagnet, the lower end of the valve is formed with a portion or transverse rib 22 which rests upon an abutment or plug 23 in the lower end of the tubular body, this plug being formed with an air

vent 24. By reason of the rib 22 in conjunction with the faces 20, 21, the valve is rendered perfectly balanced against the suction in the cylinders so that the only factors in the operation thereof are the pull of the magnet 4 and gravity. The full portion of the valve 18 directly above the reduced portion 19 normally covers the outlet port 3 of the body, and when the magnet is sufficiently energized this port 2 is uncovered so that the air is drawn by suction in the engine cylinders through the port 13, chamber 9, port 2, through the portion of the tube between the faces 20 and 21, outlet port 3, chamber 10, outlet pipe 16 to the manifold.

As before stated, the magnet is preferably wound on a spool and placed on the tube against the head 5 and a head or nut 20 turns on the body 1 against the lower head 6 and a nut 26 screws on the upper end of the body against the upper head 5. These nuts 25, 26 may be manipulated to adjust the relative position 25 of the magnet and core, to regulate the pull of the magnet on the core so that the device can be adjusted to operate at different amperages. But I prefer to make this adjustment by the use of the sections 34 hereinafter described.

The head 5 is provided with binding posts 27, 28 connected to the opposite ends of the magnet windings.

The amount of movement of the valve is controlled or limited by adjustable means on the upper end of the body 1 and carrying a stop arranged in the path of the core 17 or the extension 29 thereof.

This means is here shown as a cap 30 threading on the upper end of the tubular body 1 and carrying a screw 31 threading in the top of the cap.

The body 1, casing 7, heads 11, 12 and 5 and 6, and cap 30 are formed of a non-magnetic material as brass, but the screw 31 is formed of a magnetic material as iron and also serves as a means for holding the valve open or as a precaution against jarring loose during the vibrations to which it is subjected, and in order to prevent the core from sticking to the magnet 31, the magnet is provided with an insert 32 of non-magnetic material with which the upper end of the core engages. By turning the cap 30 more or less onto the tubular body, the extent of movement of the valve can obviously be regulated. The cap 30 is held in its adjusted position by a spring pressed retaining member 33.

To adjust the valve piece to operate at different amperages, the valve may be provided with one or more sections 34 or perforated plugs before referred to, which are placed on the extension 29 of the core. These may be non-magnetic and act to additionally weight the core or may be

magnetic, and as they are arranged on the opposite side of the center of the magnet from that on which the greater part of the core and valve are arranged, serve to raise the center of the core relatively to the center of the magnet so that a current of greater amperage is required to lift the core and valve than when the core is unprovided with said sections. As here illustrated, said sections thread on the extension 29 of the core. As here shown, there are two sections for the purpose of screwing one against the other jamb nut fashion to positively hold them in adjusted position.

In Fig. 5 is shown a diagram of the electrical connection of this air valve. 35 designates the engine, 36 the generator, and 36^a the automatic cut out or circuit breaker between the generator and the storage battery 37. 38 is the lighting circuit or load circuit. The binding posts 27, 28 are connected in one of the leads from the generator between the generator and the automatic cut out 36.

In Fig. 6, 35^a and 35^b designate the engine and magneto of a Ford power plant. 38^a is the load or lighting circuit and 27, 28, the binding posts of the magnet of my valve, the magneto, load circuit and magnet being grounded.

This device may be supported on the engine by the pipe threading into the manifold of the engine or may be supported by a bracket 40 which may be attached to the engine any place there is a bolt or screw as one of the screws 40^a which connects the head of the engine cylinders to the cylinders as seen in Fig. 7^a or to one of the screws 41 by means of which the carburetor is bolted to the intake manifold as seen in Fig. 7. The bracket has an opening through which the tubular body 1 extends, and the body is secured to the bracket in any suitable manner as by a nut 42.

In engines in which the manifold is enclosed, it is preferable to couple the inlet 14 at the same opening where the vacuum pipe 420 of the gasoline feed is connected. As shown diagrammatically in Fig. 8 the vacuum pipe 420 and my device 43 are connected to different branches 42^a, 43^a of the coupling, the third branch 44 of which is connected to the manifold.

The valve is also preferably provided with an additional air inlet opening for cold air here shown as a valve 45 communicating with the inlet chamber 9 of the casing 7 and having a cap 46 rotatable to bring a hole 47 therein into and out of alignment with a hole 48 in the body of said valve 45.

In operation, when the engine reaches a predetermined speed and hence the current generated by the generator 36 reaches a predetermined value the magnet 4 will be energized to lift the core 17 and cause the

valve 18 to uncover the port 2 so that auxiliary air enters the casing 7 and passes into the engine cylinders. The value of the current required varies in different power plants and the device is adjusted to different power plants by means of the sections 34 or by shifting the magnet lengthwise of the body. 1. Also vibration of the valve and core is prevented by means of the supplemental magnet 31. This magnet 31 also tends to hold the valve open until the amperage has dropped a predetermined amount, for instance in some engines the valve opens when the engine is running fast enough to cause the generator to produce a current of eight amperes and by reasons of the magnet 31 the valve will be held open until the engine runs slow enough to produce say only 6 amperes.

Most internal combustion engine power plants use a generator which produces a direct current. In the Ford cars, the magneto produces an alternating current and the device when applied to Ford cars requires a magnet winding of a different size wire from the windings of the device adapted for other cars.

What I claim is:

1. An auxiliary air intake valve for internal combustion engines comprising a tubular body having inlet and outlet ports extending through the periphery thereof, a casing encircling the body and formed with a partition between its ends located between said ports, the casing enclosing inlet and outlet chambers on opposite sides of the partition communicating with said ports, the inlet chamber being formed with an inlet port and the outlet chamber with an outlet port, magnet windings encircling the tubular body above said casing, a sliding core within the tubular body and a sliding valve within the tubular body and connected to the core and extending into the portion of the body enclosed by the casing in position to control the flow through the ports of the tubular body and from the intake to the discharge chamber of the casing, substantially as and for the purpose specified.

2. An auxiliary air intake valve for internal combustion engines comprising a tubular body having external threads thereon and formed with inlet and outlet ports extending through the threaded periphery thereof, a casing threading on the body and formed with a partition between its ends and chambers on opposite sides of the partition, the casing having an inlet port opening into the inlet chamber, and an outlet port opening into the outlet chamber and the partition being located between the ports of the tubular body, electromagnet windings around the body above the casing, a sliding core within the tubular body and the windings, a sliding valve located in a portion of the tubular body enclosed by the

casing and arranged to control the ports, the valve forming an extension of the core and having opposing faces whereby the valve is substantially balanced against suction, substantially as and for the purpose set forth.

3. An auxiliary air intake valve for internal combustion engines comprising a threaded tubular body having inlet and outlet ports spaced apart along the length thereof, a casing encircling the body and including a part having an intermediate transverse partition threading on the body into a position between the inlet and outlet ports, the partition separating the casing into inlet and outlet chambers, and the casing having also inlet and outlet ports opening into said chambers respectively, heads threading on the body against the ends of said part, a valve movable in the portion of the tubular body enclosed by the casing and arranged to control inlet and outlet ports, and means for operating the valve, substantially as and for the purpose described.

4. An auxiliary air intake valve for internal combustion engines comprising a tubular body having external threads thereon, and formed with inlet and outlet ports extending through the threaded periphery thereof, a casing threading on the body and formed with a partition between its ends and between said ports, and chambers on opposite sides of the partition, the casing having an inlet port opening into an inlet chamber, and an outlet port opening into the outlet chamber and said body, electromagnet windings around the body above the casing, a core within the tubular body and the windings, a valve located in the portion of the tubular body enclosed by the casing and arranged to control the ports in the tubular body, the casing being open at its ends and heads threading on the tubular body at opposite ends of the casing, substantially as and for the purpose set forth.

5. An auxiliary air intake for internal combustion engines comprising a tubular body having inlet and outlet ports, the body having a threaded portion, an electromagnet encircling the portion of the casing, heads at opposite ends of the magnet, nuts threading on the body against the outer faces of the heads, a head threading on the body below the magnet, a casing encircling the body below the last mentioned head and having a transverse partition between its ends formed with a perforated threaded opening threading on the body against the last mentioned head, the partition separating the casing into inlet and outlet chambers having inlet and outlet ports respectively, a fourth head threading on the body against the lower end of the casing, a core located in the body and extending into the portion

thereof enclosed by the magnet windings, and a valve movable in the portion of the body enclosed by the casing and arranged to control the inlet and outlet ports, the 5 valve forming an extension of the core, substantially as and for the purpose described.

6. An electrically operated auxiliary air intake valve including a tubular body having inlet and outlet ports opening through 10 the periphery thereof at points spaced apart lengthwise of the body, the body having an abutment at one end formed with a vent, a sliding balanced valve in the body ar-

ranged to control said ports and having opposing faces on opposite sides of the outlet port and also a reduced portion at its end for normally resting on said abutment, an electromagnet and a core within the body and connected to the valve, substantially as and for the purpose specified. 15 20

In testimony whereof, I have hereunto signed my name, at Syracuse, in the county of Onondaga, and State of New York, this 7th day of June, 1918.

JOHN B. WEST.
